MANUFACTURE OF CREPE THREADS OR
FABRICS MADE OF OR CONTAINING CEL-
LULOSE ESTERSWilliam Alexander Dickie, Spondon, near Derby,
England, assignor to Celanese Corporation of
America, a corporation of DelawareNo Drawing. Application November 9, 1935, Se-
rial No. 49,031. Renewed October 25, 1938. In
Great Britain November 27, 1934

7 Claims. (Cl. 117—2)

This invention relates to the manufacture of crepe threads or fabrics made of or containing cellulose esters.

U. S. Patent No. 1,966,440 describes the production of crepe threads of cellulose acetate or other organic ester of cellulose that have been saponified at intervals along their length and then twisted to a high degree, which threads are able to give an enhanced crepe effect to fabrics by reason of the different reactions of the saponified and unsaponified parts of the threads to the shrinking treatment employed to bring out the crepe effect.

It has now been found that if intermittently saponified cellulose acetate or other cellulose ester threads are given a crepe twist in a hot aqueous medium, e. g. in a steam twisting or hot water twisting process as described in, for example, British Patent Nos. 437,019, 438,590 and 438,591, the threads enable particularly useful effects to be produced in fabrics, including attractive results that are not otherwise obtainable. Probably owing not only to the differential reaction of the different parts of the threads to the shrinking treatment to which the fabric is subjected, but also to the different reactions of the saponified and unsaponified parts to the steam or hot water treatment during twisting, the threads exhibit a controlled irregularity of distorting power that goes to produce a novel crepe effect on the fabric.

The degree to which the effect is present can be varied by altering the length and frequency of the saponified parts of the threads and by varying the extent to which saponification is effected. The saponification may be partial or complete, and may be merely superficial or may extend throughout the whole of the thread.

In some cases the crepe effect resembles that commonly known as "moss crepe" which necessitates the use of a special weave, whereas with the use of the threads according to the invention the effect is obtained with the plain weave ordinarily used for crepe fabrics.

U. S. Patent No. 1,966,440 describes methods for effecting the saponification intermittently on the threads, which methods may be adopted for the purpose of the present invention either in conjunction with the saponifying agents mentioned in that specification or with the agents described in U. S. Patent No. 2,053,766 and British Patent Nos. 417,220, 428,224, 429,103, 430,349, 430,350, 430,351, 431,701, 432,027, 435,806, 440,034 and 441,544 to which specifications reference may be had for details as to the carrying out of the saponification with such agents.

The threads may be twisted before being intermittently saponified, the final twist being added after saponification, in a steam or hot water twisting process as described above. Thus when the threads are intermittently saponified concomitantly with their production, as described in U. S. Patent No. 1,966,440, any desired twist may be inserted in the thread, e. g. by means of a cap spinning device, the final or creping twisting step being carried out subsequently.

The crepe threads according to the invention may be woven into fabrics in any suitable manner, for example the weft alone may be wholly or partially composed of such threads, or the warp also may contain them. It is found convenient in general, however, to employ threads of relatively low twist in the warp, and to employ as the weft both crepe threads having a left-hand twist and crepe threads having a right-hand twist. The threads having right-hand twist and those having left-hand twist may be incorporated in any convenient manner, for example pairs of weft threads of right-hand twist may alternate with pairs of threads of left-hand twist. For example, the threads may be used as weft with either low twist cellulose acetate or other cellulose ester warps, saponified cellulose acetate or other cellulose ester warps or viscose or other cellulosic warps, or intermittently saponified cellulose acetate or other cellulose ester warps, and the resultant fabrics may either be dyed in a solid shade or cross-dyed.

While the ability of the intermittently saponified yarn to receive cross-dyed effects may be used to obtain pleasing cross-dyed fabrics, it is to be noted that the fabric even when dyed in solid colours is most attractive in appearance because of the special crepe effect imparted by reason of the different reactions of the saponified and unsaponified portions to the twisting and shrinking treatments. When the yarn is intended for cross-dyeing, the lengths and grouping of the saponified and unsaponified parts should preferably be such as to avoid the production of striped effects in the woven fabric; a long, irregular grouping, especially in weft yarn, is therefore advisable.

The effects obtained in the crepe fabrics according to the invention are substantially permanent, being particularly resistant to washing and ironing.

What I claim and desire to secure by Letters Patent is:—

1. Process for the production of crepe fabric from thread containing filaments of cellulose acetate or other organic ester of cellulose, which

comprises saponifying the filaments at intervals along the length of the thread, subsequently twisting the thread to a high degree in a hot aqueous medium, forming a fabric containing the 5 twisted thread, and subjecting said fabric to a scouring treatment whereby a crepe effect is produced in the fabric.

2. Process for the production of crepe fabric from thread containing filaments of cellulose acetate or other organic ester of cellulose, which 10 comprises saponifying the filaments at intervals along the length of the thread, subsequently twisting the thread to a high degree in the presence of steam, forming a fabric containing the 15 twisted thread, and subjecting said fabric to a scouring treatment whereby a crepe effect is produced in the fabric.

3. Process for the production of crepe fabric from thread containing filaments of cellulose acetate or other organic ester of cellulose, which 20 comprises superficially saponifying the filaments at intervals along the length of the thread, subsequently twisting the thread to a high degree in the presence of steam, forming a fabric containing 25 the twisted thread, and subjecting said fabric to a scouring treatment whereby a crepe effect is produced in the fabric.

4. Process for the production of crepe fabric from thread containing filaments of cellulose acetate or other organic ester of cellulose, which 30 comprises twisting the thread, saponifying the twisted filaments at intervals along the length of the thread, subsequently further twisting the thread to a high degree in the presence of steam, 35 forming a fabric containing the twisted thread, and subjecting said fabric to a scouring treat-

ment whereby a crepe effect is produced in the fabric.

5. Process for the production of crepe fabric from thread containing filaments of cellulose acetate or other organic ester of cellulose, which 5 comprises twisting the thread, saponifying the twisted filaments at intervals along the length of the thread, subsequently further twisting the thread to a high degree in a hot aqueous medium, forming a fabric containing the twisted thread, 10 and subjecting said fabric to a scouring treatment whereby a crepe effect is produced in the fabric.

6. Process for the production of crepe fabric from thread containing filaments of cellulose acetate or other organic ester of cellulose, which 15 comprises producing a plurality of filaments of cellulose acetate or other organic ester of cellulose, associating said filaments as a thread, and concomitantly with such production saponifying the filaments at intervals along the length of the 20 thread, subsequently twisting the thread to a high degree in the presence of steam, forming a fabric containing the twisted thread, and subjecting said fabric to a scouring treatment whereby 25 a crepe effect is produced in the fabric.

7. Process for the production of crepe fabric from thread containing filaments of cellulose acetate or other organic ester of cellulose, which 30 comprises saponifying the filaments at intervals along the length of the thread, subsequently twisting the thread to a high degree in hot water, forming a fabric containing the twisted thread, and subjecting said fabric to a scouring treatment whereby a crepe effect is produced in the fabric.

WILLIAM ALEXANDER DICKIE.
